Wayne L. Aderman, Rochester, Minn., assignor to
Motorola, Inc., Franklin Park, Ill., a corporation
of Illinois

Filed Nov. 6, 1967, Ser. No. 9,277

Term of patent 14 years

(Cl. D56—4)

FIG. 1

FIG. 3

FIG. 2

FIG. 4

FIGURE 1 is a fragmentary front elevational view of a control panel for a television receiver or similar article, showing my new design;

FIGURE 2 is a cross-sectional view, partly in side elevation, taken along line 2-2 in FIG. 1 to show the front contour of the panel;

FIGURE 3 is a cross-sectional view, partly in top plan, taken along line 3-3 in FIG. 1 to show the front contour of the panel; and

FIGURE 4 is a front elevational view thereof, to a reduced scale.

The broken line showing of a representative television set on which the panel may be mounted and of legible matter is for illustrative purposes only. The sides and

bottom of the lower portion of the panel, not shown, terminate as shown in FIGS. 2 and 3.

I claim:

The ornamental design for a control panel for a television receiver or similar article, as shown and described.
